UNITED STATES PATENT OFFICE.

BERNARD G. STERN, OF CLEVELAND, OHIO.

COMBINATION FAUCET HOUSING.

Application filed October 12, 1925. Serial No. 61,954.

To all whom it may concern:

Be it known that I, BERNARD G. STERN, a citizen of the United States, residing at Cleveland, in the county of Cuyahoga and 5 State of Ohio, have invented a certain new and useful Improvement in a Combination Faucet Housing, of which the following is a full, clear, and exact description, reference being had to the accompanying drawings.

This invention relates to plumbing fixtures and especially to a combination faucet for a kitchen sink. The essential object is to provide a cover for such a fixture which 15 may be secured in position by means including the faucet. A further object is to provide a cover which may be easily secured in place over the faucet and which will permit the faucet parts to be made 20 rough or semifinished and at the same time be in easily accessible position to facilitate adjustment or repairs.

Further objects include the provision of a soap container for the cover in such relation 25 thereto that a neat and balanced appearance of the entire ensemble is preserved.

Further objects will become apparent from the following description relating to the accompanying drawings wherein I have 30 shown a preferred form. The essential characteristics will be summarized in the claims.

In the drawings, Fig. 1 is a front elevation showing my cover applied to a combination faucet fixture; Fig. 2 is a substantially central sectional plan view showing the parts of the faucet in elevation; Fig. 3 is an end elevation of my cover; Fig. 4 is a transverse section as indicated by the 40 line 4-4 in Fig. 1; Fig. 5 is a cross-section as indicated by the line 5-5 in Fig. 2; Fig. 6 is a transverse cross section as indicated by the line 6-6 in Fig. 5, and Fig. 7 is a fragmentary cross-section showing 45 a slightly modified form of my cover retaining means.

I propose to make my cover of any suitable material, preferably china or of an enameled casting. The cover has openings 50 through which the valve operating stems may project and as shown is arranged to be held against the panel or sink apron by the use of nipples surrounding the stem and bearing against the outer surface of the 55 cover. The cover as shown has embodied

therein a soap container suitably placed relatively to the valve parts to provide adequate clearance while maintaining a balanced appearance.

Referring in detail to the drawings and 60 indicating the various parts by suitable characters, 1 and 2 represent a pair of supply pipes to which are secured valve bodies 3. Leading from the valve bodies and secured thereto in any suitable manner, I 65 have shown an outlet branch line 4 which communicates through an elbow 5 with a spout or nozzle 6. The nozzle as shown is arranged to be swung from side to side, this arrangement being a common one for discharging hot or cold water or both in the desired direction. The stems of the valves are indicated at 7 and are shown as having suitable removable handles at 8.

My valve body cover or escutcheon has 70 an outer wall portion 10, and side, top and bottom walls 11, 12 and 13 respectively. The outer wall 10 merges into both the side, upper and lower walls in very gradual curves whereby the exterior of the cover is very easily cleaned and whereby casting or molding of the cover is facilitated. The general cross sectional shape of the cover 75 as shown particularly in Fig. 6 is preferably that of half an ellipsoid. The wall 13 may be slotted as at 15 to allow the cover to be easily put in place over the discharge spout as shown particularly in Figs. 2 and 4. Openings 16 are provided in the forward 80 portion 10 of the wall for receiving the valve stems 7.

To secure the cover in place, I preferably 85 employ nipples or escutcheon holders 17 which I may slip over the stems before the handles are attached and which are provided with external threads 18 for engaging similar threads in the packing nuts 19. Suitable resilient washers 9 may be employed beneath the nipples to prevent chipping or marring the material of the cover and to lock the nipples against unscrewing. These nipples may be screwed down until 90 the entire rear edge or brim of the cover is brought securely against the apron of the sink indicated at W.

It is within the spirit of my invention, to 95 alter the cover securing means as conditions may require, the essential feature as previously mentioned being that the cover 100 shall be virtually secured in position by

means of the faucet parts as distinguished through which the stems and spout of the for instance from securing the cover to the faucet project, and means associated with panel or apron of the sink by means independent of the faucet.

In Fig. 7, I have shown a modified construction of escutcheon holding means particularly adaptable to connections where there is a variation in the distance between the supply pipes. Such variation may be taken care of so far as the faucet is concerned by the provision of slip joints. As shown, the opening 16^a may be larger or elongated while the flange 16^b on the nipple covers greater area to insure a complete closure irrespective of the position of the nipple with respect to the opening.

One of the features of my invention is that a container for soap may be made a part of the cover and so arranged that the general appearance of the cover is enhanced by its provision, while it in no way interferes with the valve parts. The container bottom indicated at 20 is made a part of the upper wall of the cover as shown especially in Fig. 5 and is below the general surface of the cover and connected thereto at its ends by end wall portions 21. Forwardly this bottom merges into the cover wall at 22 and a brim 23 rises from this merging line and curves outwardly and upwardly as shown. This brim turns rearwardly at the corners of the receptacle and merges into the cover wall substantially at its rear edge. It will be noted that by reason of the central position of the container plenty of clearance is had for the valve bodies as well as for the branch line 4 while by reason of the container being depressed within the body, the container may be made of adequate size yet in pleasing proportion in regard to appearance.

In making my cover, any suitable material may be employed. If the article is to be made of china, the walls may be quite heavy as shown to provide against breakage, while if cast or stamped metal is employed, they may be correspondingly lighter. I am aware that my invention is capable of modification and I do not wish to limit myself in carrying out my invention to mere constructional details.

I claim:

1. In combination with a sink faucet arranged in front of the sink apron and having a supply leading thereto, a cover substantially concealing the body of the faucet and secured to said apron by means associated with the faucet.

2. In combination with a sink faucet arranged in front of the sink apron, a cover to shroud the faucet and having openings

through which the stems and spout of the faucet project, and means associated with the faucet for holding the cover in position.

3. In combination with a sink faucet for admitting hot and cold water to a single spout and having valve operating stems, a cover substantially concealing the body of the faucet and adapted to lie against the sink apron, and means associated with the stems for holding the cover in place.

4. In combination with a dual sink valve arranged in front of the sink apron and having a single outlet, a cover substantially concealing the valve body, said cover having a brim extending to the apron, and members secured to the valve for maintaining the brim in contact with the apron.

5. In combination with a pair of valves arranged in front of a panel, a removable single piece cover substantially concealing the valve bodies and the inlet and outlet connections thereto, having openings arranged to receive the valve stems and means projecting through said openings and bearing against the outer wall of the cover for holding the edges of said cover against the panel.

6. In combination with a faucet fixture formed of a plurality of valve bodies having a common outlet, a cover adapted to conceal the bodies and the connections immediately adjacent thereto, and a soap container integrally formed with said cover and having bottom and side wall portions extending inwardly from the general body of the cover.

7. In combination with a dual sink faucet having a centrally placed spout for discharging hot and cold water, an elongated cup-shaped cover concealing the body of the faucet and connections immediately adjacent thereto, and a soap container integrally formed with said cover overlying and depressed inwardly toward said spout.

8. In combination with a faucet fixture having a valve body and the usual packing nut, and an outlet connection arranged forwardly of a wall, a cover arranged to conceal said faucet parts and arranged to be held in position by a member substantially rigid with the valve body, said cover being outwardly curved on its exterior surfaces and arranged to lie against the wall, and a soap container having a brim substantially flush with the upper wall portion of said cover, the bottom and side wall portions of said container extending downwardly within the cover.

In testimony whereof, I hereunto affix my signature.

BERNARD G. STERN,
